JAY A. SEAGROVES, OF NEOSHO, MISSOURI.

WATCH-GLASS GRINDER.

1,010,506.

Specification of Letters Patent.

Patented Dec. 5, 1911.

Application filed March 24, 1910, Serial No. 551,310. Renewed April 29, 1911. Serial No. 624,146.

To all whom it may concern:

Be it known that I, EDWARD R. MATTERS, a citizen of the United States, residing at Neosho, in the county of Newton and State of Missouri, have invented a new and useful Watch-Glass Grinder, of which the following is a specification.

The device forming the subject matter of this application is adapted to be mounted in 10 a jeweler's lathe, to be employed for grinding watch glasses and the like.

It is the object of this invention to provide rotatably mounted grinding elements of novel and improved form; to provide a 15 novel means for mounting the grinding elements for rotation; to provide a novel means for advancing one of said grinding heads toward the other; and for maintaining the adjustable grinding head in the position to 20 which it has been advanced.

In the drawings, Figure 1 is a side elevation; Fig. 2 is an end elevation; Fig. 3 is a longitudinal section; Fig. 4 is a detailed perspective of the cam shaft; Figs. 5 and 6 are 25 elevations of the grinding heads; and, Fig. 7 is a section of the cam shaft on the line A—B of Fig. 4.

The device includes, as a primary and fundamental element, a U shaped supporting member 1, the arms 2 of which terminate in heads 3 and 4, these heads having openings in which are mounted for rotation, respectively, a shaft 5 and a shaft 6. The shaft 5 is provided with a collar 7, preferably integrally formed, and adapted to bear against the end of the head 3 to prevent the shaft 5 from moving toward the shaft 6. A grinding head 8 is provided, the same having an outstanding shoulder 9, provided with 10 a stud 10, adapted to be threaded into an opening 14 in the end of the shaft 5. The collar 7 is positioned upon the shaft 5 in such a way that when the shoulder 9 of the head 8 is rotated against the end of the shaft 5, the shoulder 9 will not be bound against the end of the head 3. A grinding head 11 is provided, having an opening 15, in which may be secured by threading or otherwise, the reduced end 26 of the shaft 6. This 15 shaft 6 is slidably mounted in the head 4, and the elements 8 and 11 have, upon their adjacent surfaces, facings 12 preferably fashioned from cork.

Slidably mounted in the head 4, is a pin

15, provided at its outer end with a milled 55 thumb piece 16. In the inner end of the pin 15 there is a concaved socket 17, in which the rounded end 18 of the shaft 6 is adapted to rotate. The pin 15 has a longitudinally extended slot 19, terminating within the 60 contour of the pin.

Mounted transversely in the head 4 below the pin 15 is a shaft 20. This shaft 20 has a rounded transverse groove 21, adapted to form a continuation of the opening in the 65 head 4 in which the pin 15 is mounted, and owing to the presence of the groove 21, the pin 15, may under proper conditions, be inserted in place within the head 4.

The shaft 20 has a cam face 22, defining 70 a shoulder 24 in one end of the shaft. The flat longitudinal face of the slot 19 in the pin 15 intersects the periphery of the opening in which the shaft 20 is mounted, and thus the shoulder 24 upon the shaft 20 is 75 engaged, preventing the shaft 20 from being accidentally withdrawn, since, either the shoulder 24 or the groove 21 of the shaft 20 are at all times in engagement with the pin 15.

The shaft 20 has at one end, a radially disposed handle 23. It will be seen that this handle 23 is so positioned with respect to the groove 21 that if the groove 21 is to be so positioned with respect to the opening in 85 the head 4 in which the pin 15 is mounted, that the pin 15 may be withdrawn, the handle 23 must upstand above the horizontal, in the position indicated in dotted line in Fig. 1; whereupon the pin 15 may be withdrawn. As soon as the handle 23 is rotated in the direction of the arrow A, the shoulder 24 is first positioned to engage the pin 15, thus preventing the withdrawal of the shaft 20; and subsequently the cam face 22 of the 95 shaft 20 is made to enter the slot 19, thus preventing the withdrawal of the pin 15.

It will be seen that the handle 23 is so positioned with respect to the face 22 that the handle acts gravitationally to maintain 100 the said face within the contour of the slot 19 of the pin 15, and to cause the cam face 22 to bind upon the pin 15 within the contour of the slot therein. Thus, as soon as the handle 23 is swung over in the direction 105 of the arrow A, past the vertical, the handle 23 will act, by its own weight, to bind the pin 15 in position. In Fig. 3 the shaft 20

has been swung in the direction of the arrow A, to a point about midway between the positions indicated by the solid and dotted line positions of the handle 23 in Fig. 1. The heads 8 and 11 may readily be removed from their respective shafts, 5 and 6 when it is desired to renew the cork facings 12 to renew the same.

In practical operation the end of the shaft 5 which is specifically denoted by the numeral 27 in Fig. 3, is inserted into the chuck of a lathe, rotating the grinding head 8. The pin 15 may be slid in the head 4 to advance the grinding head 11 so that the cork facings 12 may bear against the watch glass which is to be ground, the pin 15 being readily located in a fixed position by manipulating the handle 23.

While the grinding head 8 is being rotated as above described, the article which is being polished, may be held between the grinding heads, and against movement, by the hand of the operator, or the article may be held in a suitable tool, or in any other manner. If desired, the U-shaped supporting member 1 may also be steadied by one hand of the operator.

Having thus described the invention what is claimed is:—

1. A device of the class described comprising spaced arms; axially aligned shafts rotatably mounted in the arms transversely of the same, one of the shafts being slidably mounted; grinding heads upon the adjacent ends of the shafts; means for advancing the slidably mounted shaft; and a device operating gravitationally to bear against the advancing means, to lock the same.

2. A device of the class described comprising spaced arms; axially aligned shafts rotatably mounted in the arms transversely of the same, one of the shafts being slidably mounted; grinding heads upon the adjacent ends of the shafts; a pin slidably mounted in one of said arms and arranged to bear against the slidably mounted shaft; and a

cam mounted in the last named arm and arranged to bear against the pin.

3. A device of the class described comprising a supporting member having spaced arms; axially aligned shafts rotatably mounted in the arms transversely of the same, one of the shafts being slidably mounted; grinding heads upon the adjacent ends of the shafts; a pin slidably mounted in one of said arms and arranged to bear against the slidably mounted shaft, the pin having a longitudinally disposed slot terminating within the contour of the pin; a shaft transversely mounted in the last named arm and having a cam face arranged to bear against the pin within the contour of the slot, the shaft being transversely grooved to provide for the passage of the pin into its supporting arm.

4. A device of the class described comprising a supporting arm; a shaft slidably and rotatably mounted in said arm; a pin slidably mounted in said arm and arranged to bear against the shaft, the pin having a longitudinally disposed slot terminating within the contour of the pin; a shaft transversely mounted in said arm and having a cam face arranged to bear against the pin within the contour of the slot, the shaft being transversely grooved to provide for the passage of the pin into its supporting arm; the last named shaft having a radial handle operating gravitationally to maintain the cam within the slot and in bearing upon the pin; a grinding head upon the first named shaft; and a co-operating grinding head supported for rotation adjacent thereto and adapted to receive driving means.

In testimony that I claim the foregoing as my own, I have hereto affixed my signature in the presence of two witnesses.

EDWARD RICHARD MATTERS.
